UNITED STATES PATENT OFFICE.

BENJAMIN E. D. STAFFORD, OF PITTSBURGH, PENNSYLVANIA, ASSIGNOR TO FLANNERY BOLT COMPANY, OF PITTSBURGH, PENNSYLVANIA.

“FLEXIBLE STAY-BOLT CONNECTION FOR BOILERS.

1,250,240.

Specification of Letters Patent. Patented Dec. 18, 1917.

Application filed October 30, 1915. Serial No. 53,868.

To all whom it may concern:

Be it known that I, BENJAMIN E. D. STAFFORD, a citizen of the United States, and a resident of Pittsburgh, in the county of Allegheny and State of Pennsylvania, have invented certain new and useful Improvements in Flexible Stay-Bolt Connections for Boilers; and I do hereby declare the following to be a full, clear, and exact description of the invention, such as will enable others skilled in the art to which it appertains to make and use the same.

My invention relates to an improvement in flexible stay-bolt connection for boilers, and is an improvement on the construction disclosed in application Serial Number 44,638 filed by Peter F. Gallagher, August 5th, 1915.

In the application above referred to, the roof plate or outer sheet of the boiler is provided with an opening of a size sufficient to receive the end of the sleeve carrying the head of the bolt, the sleeve being secured in said opening by welding.

In the device as illustrated in said application, the sleeve has no direct bearing on the roof plate and hence the welded joint has to sustain the hammer blows in riveting up the end and all the stresses, and particularly the boiler pressure, to which the bolt is subjected when in use.

The object of my invention is to overcome this defect by seating the sleeve on the roof plate or outer sheet of the boiler, and welding the sleeve to the outer face of the plate, so that the plate forms a direct abutment and support for the sleeve.

In the accompanying drawings, Figure 1 is a view partly in elevation and partly in section showing the manner of attaching the sleeve to the roof plate of the boiler; Fig. 2 is a view showing the application of the bolt to a roof plate that is at an angle to the crown sheet and Figs. 3 and 4 show curved plates counterbored to receive the sleeves.

1 represents the roof plate or sheet of a locomotive boiler, provided with an opening 2 for each stay bolt, the said opening 50 being slightly larger than the shank 3 of the bolt, so as to permit of relatively free movement of the shank in said opening. The plate 1 is counterbored on its outer surface around the opening 2, to receive and 55 form a seat for the end of the sleeve 4, the

said end of the sleeve being machined off to make a close fit with the seat or abutment 4 formed by counterboring the plate 1. This sleeve is provided interiorly with a curved seat 5 for the spherical head 6 of the bolt 3, and is provided exteriorly at its outer end with threads for the attachment of the cap 7, the inner face of the latter being curved to conform to the curvature of the head of the bolt, sufficient clearance however being left for a limited movement of the head of the bolt in the sleeve and cap, or an equal movement of the sleeve and cap on the head. The outer edge or periphery of the cap is made hexagonal, or angular 70 for the attachment of the wrench employed in screwing and unscrewing the cap.

The inner end of the sleeve is preferably made to flow outwardly, as shown, so that after it is welded to the sheet, the metal of the sleeve will underlie the metal of the weld and thus lock the sleeve solidly in place.

In assembling the parts, the sleeves are properly placed with relation to the bolt opening in the outer plate, after which the welding composition or filler is applied at the outside as at 8, between the sleeve and the shoulder 9 formed by counterboring the outer plate, and also preferably at the inside at the juncture of the sleeve and plate 85 as at 10, after which the weld is effected by the oxy-acetylene welding method, or by electrically welding the parts. The welding fuses the metals so that the union between the plate and sleeve is of a homogeneous 90 character thereby securing all of the advantages of a sleeve integral with the plate as obtained.

In Fig. 2 I have shown a pressed steel sleeve applied to an outer plate set at an angle to the crown sheet 10^a, the sleeve being welded to the plate at the outer edge only of the sleeve.

In Figs. 3 and 4 I have shown curved plates, one convex and the other concave, 100 counterbored for the reception of a sleeve or bushing.

The head of the bolt rests within the sleeve or the curved seat 5 in the latter in the usual and well known manner, and is 105 covered, and protected by the removable cap 7. The opposite end of the bolt is secured to the inner or crown sheets usually by threads as shown in Fig. 2.

In Fig. 2 I have shown the bolt 3^a with a 110

threaded outer end to which the semi-spherical head 6^a is secured and a button head inner end for attachment to the inner sheet. These details and the manner of securing 5 the bolt to the inner sheet are immaterial as my invention relates more particularly to the method of mounting the sleeve 10 the roof plate.

In the prior methods of securing the 10 sleeves or bushings to the roof plate of a locomotive boiler, for the application of a flexible stay bolt, the end of the sleeve has been located within the opening in roof plate, and secured by threads, as in the Tate 15 type of stay bolt, or by fusing as in the Gallagher type. Both of these methods necessitate the employment of a larger hole or opening than is desirable; they limit the dimensions of the sleeve section and leave 20 the sleeve unsupported except by the threads or weld.

By counterboring the plate for a clean 25 and straight bearing for the bushing, sleeve or socket, which is subsequently welded in the counterbore, I am enabled to use a much 30 smaller opening in the plate and thus conserve its strength, and at the same time provide a solid abutment for the sleeve on the plate, which is sufficient to withstand the 35 hammer blows in testing the bolt, in riveting up the end of the latter; in tightening up the caps and other shocks to which they are subjected in assembling and testing.

Again all stress on the stay bolts and 35 sleeve or bushing due to boiler pressure, is borne directly by the plate 1 instead of by the threads or welded joint.

The bushings or sleeves can be machined off to the desired angle to conform to the 40 angle of stay bolt installation, and in the case of a pressed steel socket, as shown in Fig. 2, the part that is to be milled off to conform to the angle of the outer plate, can be so shaped that when cut to the angle it 45 will approximate a true circle. The socket top however is round or circular in shape.

It is evident that many slight changes might be resorted to in the relative arrange-

ment of parts shown and described without departing from the spirit and scope of my 50 invention. Hence I would have it understood that I do not wish to confine myself to the exact construction and arrangement of parts shown and described except as required by the scope of the appended claims. 55

Having fully described my invention what I claim as new and desire to secure by Letters-Patent, is:—

1. In stay bolt connection for a boiler, the combination of a boiler plate having an 60 opening for the passage of a bolt, and a counterbore around and in communication with said opening, and a support for the head of the bolt seated in said counterbore and secured therein by welding.

2. In a stay bolt connection for a boiler, the combination of a boiler plate having an opening for a stay bolt and a concentric counterbore around and communicating with 70 said opening, a support for the head of the bolt seated in said counterbore and secured therein by welding and a cap detachably secured to the outer end of the support.

3. In a stay bolt connection for boilers, the combination of a boiler plate having an 75 opening for a stay bolt, a sleeve seated on the plate around said bolt opening and secured on said plate by welding and a cap screwed to the outer end of said sleeve for closing the bolt opening and covering the 80 head of the bolt.

4. In a stay bolt connection for boilers, the combination of a boiler plate having an opening for a stay bolt, a sleeve seated on 85 said plate around the bolt opening and welded thereto at the outer edge and also the inner side of the inner end of said sleeve and a cap detachably secured to the outer end of said sleeve.

In testimony whereof, I have signed this 90 specification in the presence of two subscribing witnesses.

BENJAMIN E. D. STAFFORD.
